CODING DEVICE

Filed July 5, 1945

HENRY E. WIRTH ^{INVENTOR}

By William D. Hall
ATTORNEY

Filed January 8, 1952. Application Serial No. 603,394. This is a continuation-in-part of my application Serial No. 370,020, filed January 10, 1945, now U.S. Pat. No. 2,581,461, issued January 8, 1952.

UNITED STATES PATENT OFFICE

2,581,461

CODING DEVICE

Henry E. Wirth, Philadelphia, Pa.

Application July 5, 1945, Serial No. 603,394

2 Claims. (Cl. 35—2)

(Granted under the act of March 3, 1883, as amended April 30, 1928; 370 O. G. 757)

1

The invention described herein may be manufactured and used by or for the Government for governmental purposes, without the payment of any royalty thereon.

Radio circuit components such as resistors or capacitors are marked according to a color code. This color code designates the size of the resistor in ohms or of the capacitor in micromicrofarads, the percentage of tolerance permitted either the capacitor or resistor, and the direct current voltage which may safely be applied to the capacitor.

It is an object of my invention to provide a coding device which permits an unskilled or inexperienced person to determine the proposed markings to be applied to a radio circuit component or to read the size and other electric characteristics of such a component. In other words, my device enables a person unfamiliar with the code to encode or decode according to the code selected.

An example of such color codes is the Radio Manufacturers Association color code. These codes are changed from time to time which would necessitate a remarking of my device but, since the codes form no part of my invention, my device is applicable to codes of various kinds.

More specifically, it is an object of my invention to provide a coding device consisting of a body, a slide mounted for movement on said body and having representations of radio circuit components thereon, a plurality of movable elements mounted on said body so as to expose selected portions thereof which are of different colors and which bear different notations thereon, and guide lines leading from the said movable elements to selected parts of the representations. These representations correspond to radio circuit elements which it is desired to encode or decode so that the position of the movable elements corresponds to the color which the connected portion of the representations should be.

My invention is obviously capable of many embodiments of which but one has been selected for illustration in the drawings and description in the specification.

The single figure of the drawings is a face or plan view.

The selected embodiment of my invention comprises a body 1 conveniently made of two pieces of thick cardboard spaced from each other in a direction perpendicular to the plane of the drawing so as to provide a passage or way 2 therethrough. In this passage or way is mounted a slide 3 which has a plurality of representations

2

of radio circuit components thereon. But one of these representations (designated at 4) is to be seen in the drawings. It comprises a front and rear view of a resistor. Pivotedly mounted on body 1 are a plurality of movable elements 5 in the form of discs. Each disc is divided into sectors of different colors as is seen at line 55 and each sector carries a numeral 6 thereon. Guide lines 7, 8, 9, 10 lead from a point adjacent each of the discs 5 to the edge of a perforation 11. Perforation 11 exposes a portion of way 2 and a part of the surface of slide 3 therein. Through perforation 11 one of the representations 4 of a radio circuit component is exposed. Additional lines 77, 88, 99, and 110 lead from the line 7, 8, 9, and 10 respectively to parts of the representations 4. Lines 7, 8, 9, and 10 are differently colored. Lines 77, 88, 99 and 110 are colored the same as the corresponding lines, 7, 8, 9, or 10 respectively.

It is believed that the operation of my device will be readily understood from the foregoing. Assume that it is desired to read the amount of an unknown resistor in ohms. Slide 3 is adjusted until a representation 4 corresponding to the unknown resistor is exposed through perforation 11. The lines 77, 88, 99 and 110 contact the corresponding lines 7, 8, 9, and 10. Discs 5 are then adjusted so that their exposed sectors correspond with the colors on those portions of the representation 4 to which each disc is connected by lines 7 and 77, 8 and 88, 9 and 99, 10 and 110 respectively. The digits or numeral 6 which are then exposed on the disc 5 are read off. In the example shown the first 3 digits or numerals represent the resistance in ohms while the right hand digit (to which the reference character 6 has been applied) represents the tolerance in percentage plus or minus.

I claim:

1. A device for encoding as code markings certain characteristics of electric circuit components or for decoding such code markings to determine such characteristics, comprising: a body; a member mounted on and movable with respect to the body; on the member, a plurality of representations of electric circuit components, each representation being marked in a code which indicates certain characteristics of the components and guide lines associated with the elements of said code; on the body, adjustable indicating means bearing code markings corresponding to those on the member and additional markings for translating the code; said body including guide lines with which the code

markings of a representation may be aligned, these lines on said body being adapted for alignment with the guide lines on said member thereby serving also to associate the member code markings with the indicating means; the indicating means being adjustable so that the code markings thereon may be matched up with the code markings of the member.

2. A device for encoding as code markings certain characteristics of electric circuit components or for decoding such code markings to determine such characteristics, comprising: a body, a member mounted on and movable with respect to the body; said member having thereon a plurality of representations of electric circuit components, each representation corresponding to a component and being marked in a code which indicates certain characteristics of the component; indicating means on said body having a plurality of portions each of which bears a code marking corresponding to one of the code markings on the member and an additional marking for translating the code marking; said body also including guide lines with which guide

lines of a representation may be aligned, said lines serving also to associate the member code markings with the indicating means; the indicating means being adjustable so that its portions bearing the corresponding code markings may be matched with the code markings of the member; an aperture in said body large enough to permit at least one of the representations including guide lines leading from the code markings of the representation to an edge of the aperture, the latter guide lines being capable of alignment at the edge of the aperture with the guide lines on the body.
